CARBON PILE REGULATOR

Martin J. Neuner, Fairview, N. J., assignor to
 Bendix Aviation Corporation, Teterboro, N. J.,
 a corporation of Delaware

Application November 1, 1948, Serial No. 57,652

2 Claims. (Cl. 201—51)

1

The present application relates to an electrical regulator and more particularly to improvements in a regulator of the type disclosed and claimed in the copending U. S. application Serial No. 612,691, filed August 25, 1945, by William G. Neild, now U. S. Patent No. 2,481,771, and assigned to the assignee of the present application.

At the present time carbon pile regulators have come into widespread use for such purposes as controlling the voltage of the output of generators and also in the governing of currents.

All of these carbon pile regulators operate on the principle of varying the pressure applied to the carbon pile; the range of effective pressure on the pile being the regulating range of the regulator.

There has now come into fairly widespread use a regulator which is of the type disclosed in the aforesaid application and which may include the usual carbon pile, one end of which is relatively fixed. Operatively associated with the other end to apply pressure on the pile is an armature and this armature is carried by a spring of the so-called diaphragm type.

The force of the electromagnet is rendered effective on the armature and the diaphragm type spring above referred to tends to urge the armature towards the pile, while the magnetic force tends to withdraw the armature from the pile so as to approximately vary the force exerted by the diaphragm spring inversely as the square of the distance between the armature and magnet so as to effect basic correspondence with changes in the magnetic force.

An object of the present invention is to simplify and improve the aforesaid type of carbon pile regulator.

Another object of the invention is to improve the structure of the aforesaid carbon pile regulator and provide a fluid or liquid medium to envelop the carbon pile and convey heat from the carbon pile to the surrounding casing.

Another object of the invention is to provide a carbon pile regulator in which a cooling fluid is carried within a sealed chamber adjacent the radiating fin portion of the regulator casing, and which chamber is provided at each end with sealing rings of the O-ring type.

Another object of the invention is to so arrange the aforesaid fluid chamber so that the same is sealed at one end by a diaphragm type armature spring, while the other end is sealed by a novel sealing bellows which permits adjustment of the pile through a suitable adjusting screw.

2

Another object of the invention is to provide in a carbon pile regulator the arrangement of a diaphragm type spring which serves the novel double function of a seal and a spring for the armature of the carbon pile.

The above and other objects and features of the invention will appear more fully hereinafter from a consideration of the following description taken in connection with the accompanying drawing wherein one embodiment of the invention is illustrated by way of example.

The drawing is a fragmentary sectional view of a regulator embodying the invention.

Referring to the drawing, there is provided a plate 1 on which there is mounted a magnet casing 2. The plate 1 and casing 2 are formed of a suitable ferro-magnetic material.

A core 5 of similar material projects from the plate 1 into an electromagnetic winding 7 about the core 5 and positioned within the casing 2. The plate 1 is fastened to the casing 2 by suitable screws 9. About the casing 2 there is provided a hollow housing or collar 11 which may be partially filled with a suitable cooling liquid or gaseous medium through an opening 13 closed by a plug 15.

The fluid medium within the housing 11 serves to cool the coil housing 2 and the housing 11 further has provided suitable radiating fins 17 to further this cooling action. A housing 20 having cooling fins 21 and of a type such as shown in U. S. Patent No. 2,427,805, granted September 23, 1947, to William G. Neild and assigned to Bendix Aviation Corporation, is fastened to the coil housing 2 by studs 22. The housing or carbon pile casing 20 has a flange portion disposed in sufficient spatiality to the magnet casing or housing 2 to preclude engagement upon longitudinal expansion of the housing 20 relative to the magnet casing 2 in response to a rise in temperature, as explained in the aforesaid U. S. patent. Mounted in the housing 20 is a non-conducting tube 25 formed of a suitable refractory material such as porcelain and locked in position by a suitable fastening spring 26. Tubular member 25 carries carbon discs 27 forming a carbon pile. Suitable channels 29 and 31 formed in the casing 20 extend along the tubular member 25 for enveloping the member 25 with a suitable fluid medium for cooling the tubular member 25 and carbon disc 27, as will be explained in greater detail hereinafter.

A contactor member 33 is positioned between one end of the carbon pile 27 and plate 36. The contactor member 33 is positioned in a cup-

shaped supporting member 38 mounted on the plate 36.

The plate 36 is shown in the drawing as positioned at one side of a diaphragm type spring 39. At the opposite side of the diaphragm type spring 39 there is positioned an armature plate 41. The diaphragm type spring 39 is clamped between the plates 36 and 41 by suitable fastening screws 43 one of which is shown in the drawing. The diaphragm 39 is formed in a circular shape of a suitable spring material and thickness. Formed in the diaphragm 39 are suitable annular corrugations 45, 46 and 47 of proper depth to provide the desired spring characteristics for matching the varying pull of the magnet as the distance between the armature 41 and magnet core 5 changes.

As shown in the drawing, the diaphragm 39 is positioned in an annular cup-shaped member 50 having a seat portion 52 on which rests an annular edge portion 55. The annular edge portion 55 of the diaphragm 39 may be clamped about the seat portion 52 and secured thereto by soldering or by other suitable fastening means.

It will be seen then that the diaphragm 39 extends across the cup-shaped member 50 and flexibly suspends armature 41 therein. Axial movement of the armature 41 in the cup-shaped member 50 is accommodated by the kinks or corrugations 45, 46 and 47 formed in the diaphragm 39 as disclosed and claimed in the co-pending application Serial No. 612,691, filed August 25, 1945, by William G. Neild, now Patent No. 2,481,771, issued September 13, 1949, and assigned to the assignee of the present application.

The latter cup-shaped member 50 as shown in the drawing is positioned within an annular flange portion 57 of the magnet housing 2 and between the magnet housing 2 and the carbon pile housing 20. There is positioned an O-shaped sealing ring 59 formed of a suitable plastic rubber-like material between the bottom of the cup-shaped member 50 and the housing 20 to provide a sealing connection for a purpose which will be described hereinafter.

At the opposite end of the carbon pile 27 there is provided a contactor member 61 positioned in a cup-shaped member 63 mounted at one end of a sealing bellows 65. The opposite end of the sealing bellows 65 is secured at 67 by soldering or other suitable means to a plug 69 secured in a casing member 71 by brazing or soldering.

Screw-threaded member 73 is fastened to the plug 69 and casing 71 by a suitable securing screw 75. Adjustably mounted in the member 73 is a screw-threaded adjustment bolt 77 which contacts one end of the member 79 slidably mounted in the plug 69 and secured at its opposite end 80 to the inner end of the bellows 65. The casing 71 is secured to the other end of the casing 20 by suitable bolts 82 and is electrically insulated from the casing 20 by suitable insulating washers 84, 86 and 88. There is further provided between the end of the casing 20 and the casing 71 an O-shaped sealing ring 90 formed of a suitable rubber-like plastic material. A tubular member 93 projects through the casing 71 and opens into the interior 95 thereof. It will be seen then that through the provision of the novel O-shaped sealing rings 59 and 90, the interior 95 of the casing 71, passages 31 and 29 in casing 20 and the interior of the cup-shaped member 50 sealed by diaphragm 39 forms a sealed chamber which may be filled with a suitable cooling liquid such as oil or with a gaseous medium such as helium.

under pressure, which may be introduced into the sealed chamber by first evacuating the same through the conduit 93, after which the fluid may be introduced thereto and the tube 93 sealed off as by pinching or soldering. The liquid cooling medium may only partially fill the sealed system and is arranged to conduct heat from the carbon pile 27 to the outer cooling fins 21 of the casing 20. However, when filled with a cooling gas such as helium under pressure, it will be seen that the diaphragm 39 serves the double function of a seal and also as a spring for the armature and that through the medium of the helium gas in the sealed chamber an advantageous damping effect upon the diaphragm spring will be effected, as well as the superior cooling effect on the carbon pile 27 noted herefore.

Moreover, in the sealed chamber immediately about the carbon pile 27 there may be provided a fluid or liquid medium to envelop the carbon pile and conduct heat from the carbon pile to the casing fins 21. One end of the chamber is sealed by the diaphragm armature spring 39, 20 while the other end is sealed by the sealing bellows 65 which permits adjustment of the pile through the adjusting screw 77 without disturbing the sealed relationship of the chamber. The sealed chamber is further effected through the 25 novel arrangement of the O-shaped sealing rings 59 and 90 at the opposite ends of the carbon pile housing 20 which rings cooperate with the cup-shaped member 50 and the casing member 71 to effect the desired sealed chamber immediately 30 adjacent the carbon discs 27 at the opposite ends and about the sides of the same for effecting the desired cooling action.

Although only one embodiment of the invention has been illustrated and described, various 40 changes in the form and relative arrangements of the parts may be made to suit requirements.

What is claimed is:

1. In a carbon pile regulator, an electromagnet including a core, a housing for said electromagnet, a stack of discs of resistant material, a casing for said discs, said casing affixed to said housing and having an end portion fitting loosely about an end portion of said housing to permit 45 expansion and contraction of said casing relative to said housing with changes in temperature, the casing having a constricted section about the assembled stack, radiating fins carried in spaced relation about the constricted section of the casing, a cup-shaped member positioned between the housing and casing, a diaphragm sealing one 50 end of the cup-shaped member, an armature carried by said diaphragm and cooperating with said core, said diaphragm having the outer edge thereof anchored to said cup-shaped member, said armature being disposed to control the pressure applied at one end of said discs, a second housing at the other end of said discs and affixed to said casing, said casing having passage 55 means extending along said discs from the interior of said cup-shaped member and the interior of said second housing, an annular ring of rubber-like material positioned between said cup-shaped member and said casing, and another annular ring of rubber-like material positioned between said casing and said second housing to provide a sealed chamber including said passage 60 means and the interior of the cup-shaped member and the interior of said second housing to hold a fluid heat conducting medium therein and adjacent the discs.

2. In a carbon pile regulator, an electromagnet including a core, a housing for said electromagnet, a stack of discs of resistant material, a casing for said discs, the casing having a constricted section about the assembled stack, radiating fins carried in spaced relation about the constricted section of the casing, a cup-shaped member positioned between the housing and casing, a diaphragm sealing one end of the cup-shaped member, an armature carried by said diaphragm, and cooperating with said core, said diaphragm having the outer edge thereof anchored to said cup-shaped member, said armature being disposed to control the pressure applied at one end of said discs, a second housing at the other end of said discs, an adjustable member mounted at the other end of said discs, an exteriorly adjustable screw extending through said second housing for effecting adjustment of said member and said discs therethrough, a sealing bellows supporting said member and surrounding said screw so as to seal the interior of said second housing, said casing having passage means extending along said discs from the interior of said cup-shaped

member and the interior of said second housing, an annular ring of rubber-like material positioned between said cup-shaped member and said casing, and another annular ring of rubber-like material positioned between said casing and said second housing to provide a sealed chamber including said passage means and the interior of the cup-shaped member and the interior of said second housing, and a sealable tubular member opening into said second housing for supplying a fluid heat conducting medium to said chamber.
